UNITED STATES PATENT OFFICE.

CHARLES T. JOSLIN, OF FEURA BUSH, NEW YORK.

SEPARABLE MULTIPLE FORM.

Application filed July 30, 1925. Serial No. 47,141.

The present invention relates to a mold or form to be used in casting posts from plastic material such as concrete or cement. More particularly it relates to molds of this 5 general character which are separable and in which a plurality of posts may be cast at one operation.

Many States and municipalities have adopted a standard post for guide railing 10 which is placed along the sides of a highway for the purpose of indicating to the drivers of vehicles a dangerous change in elevation between the highway and the land on either side. These posts are of concrete and triangular in cross-section. Heretofore, in fabricating these posts the practice has been to have a separate form or mold for each post and to cast them in a horizontal position. The posts are generally reinforced by a 20 steel bar in each corner of the triangle, and when the posts are cast horizontal it is necessary to stop the operation of pouring concrete at least twice in order that the reinforcement may be placed in proper position. This method of casting requires a 25 large number of individual forms which occupy a considerable space, the concrete must be distributed along the length of each form, and either the distributing means or 30 the forms themselves must be moved each time a form is filled.

The objects of my invention, therefore, are to provide a form or mold in which a 35 plurality of posts may be cast at one pouring operation without moving either the concrete distributing means or the form or mold, and to provide a device of this character in which the posts may be cast in a vertical position thereby permitting the reinforcement to be inserted either prior or 40 subsequent to the pouring of the concrete so that both the operation of pouring and the operation of inserting the reinforcement may be conducted without interruption.

Another object of my invention is to so 45 assemble a number of individual post-forms or molds as to greatly reduce the number of plates or units required. A further object of my invention is to provide a multiple 50 form or mold made up of a minimum of separate elements which may be readily assembled to form a unit of convenient size and in which the elements are readily separable for the purpose of removing the post 55 and cleaning and oiling the elements.

With these objects in view my invention

consists in the novel elements and arrangements and combinations thereof typically illustrated in the accompanying drawing and described below.

In the drawing, Fig. 1 represents an outside elevation view of my form or mold.

Fig. 2 is a cross-section of Fig. 1 on the line 2-2;

Fig. 3 is an enlarged elevation view of a 65 fragmentary portion of the central post used in my form;

Fig. 4 is an enlarged cross-sectional view of the central post showing fragmentary portions of the radial plates;

Fig. 5 is a broken elevation view of the concrete post which my mold is designed 70 to cast;

Fig. 6 is a top view of this post;

Fig. 7 is a half-plan view of a polygonal 75 funnel or hopper which may be used in conjunction with my form;

Fig. 8 is a vertical cross-sectional view of Fig. 7 on the line 8-8.

In considering the drawings it is to be 80 understood that they are not to scale and that for the purpose of clarity the plates which go to make up my form or mold are greatly exaggerated in thickness.

Referring to the drawing, 1, represents a 85 concrete post which is in the form of a triangular prism having rounded edges, 2 and 3, and a flat or truncated edge, 4. The top of the post which is preferably pyramidal, as shown at 5, may, of course, be flat or of 90 any other convenient form.

Referring particularly to Figs. 1 and 2 my mold comprises a base, 6, preferably of cast-iron, circular in cross-section, and provided at its center with a recess, 7, adapted 95 to receive the bottom end of the central post, 8. The post, 8, may be an integral unit, hexagonal in cross-section and provided along each vertical edge thereof with a recess adapted to receive the radial plates. 100 9. However, I prefer to construct the post, 8, of pipe, as illustrated in the drawing and give it a substantially hexagonal contour by bolting or welding along the exterior thereof plates, 10, and 11. This construction is 105 perhaps best shown in Fig. 4. The inside plates, 11, are narrower than the outside plates, 10, and the vertically extending edges of plates, 10, are slightly spaced to provide an opening into which the vertical edges of 110 radial plates, 9, may be inserted. The plates, 10 and 11, are secured to the post, 8,

by means of bolts or rivets, 12, and the plates, 10 and 11, extend from the top of post, 8, to a point somewhat above the bottom thereof, as shown in Fig. 3, thus providing a short portion of pipe, 8, which is adapted to fit rather snugly in the recess, 7, provided in base, 6. Disposed circumferentially on the top of the base, 6, are six equally spaced lugs, 13, provided with radial recesses, 14, adapted to receive the outer bottom corners of the radial plates, 9. Between each of the radial plates, 9, near the outer edges thereof, are the circumferential plates, 15, each of which forms a side of a triangular mold, and which, collectively, form the sides of an upright hexagonal prism. The vertical edges of plates, 15, are curved inwardly to a suitable radius so that the corners of the posts will be rounded. While the drawing illustrates these plates of substantial thickness, in practice, they may be very light. For this reason I prefer to reinforce them at the points shown in Fig. 2 by welding or riveting the flat bars, 16, thereon. The bars, 16, also hold the straps, 17, away from the outer edges of the radial plates so that when the nuts, 18, on the straps are tightened the circumferential plates are firmly compressed into the spaces between the radial plates. The straps, 17, are preferably of thin metal and are provided with the lugs, 19, which are adapted to receive the tightening bolts, 20.

In assembling my form or mold the post, 8, is first inserted in the center of the base. The radial plates, 9, are next positioned by placing them in the recesses of the posts and so that the lower outer corners engage the recesses in the lugs, 13. The circumferential plates are then set in position and secured by tightening the straps, 17.

When the posts are to be cast with square ends, no particular form of base is required and the plates, 10 and 11, on post, 8, may extend from end to end of the post so that the form may be assembled upon any flat surface. When it is desired to cast the post with a pyramidal or other shaped end, recesses, 21, of the desired configuration are provided in the base at the bottom of each of the triangular molds. It will thus be obvious that the posts are cast in an inverted position.

It will be clear that recesses or openings of any size or shape may be provided in the posts by placing suitable projections upon the interior of the mold. When the posts are intended to be used with cable railing it is usual to attach this railing to the posts by means of hook bolts extending through openings, 22, provided in the posts. For the purpose of forming these holes for the reception of such bolts I provide the openings, 23, in the circumferential plates. Short rounded bars such as shown by the

dotted lines, 24, in Fig. 2 may be inserted through these holes and into holes, 25, provided in the central post.

In pouring concrete into my mold I find it very convenient to use a hexagonal funnel, 26. This funnel is provided with depending grips, 27, adapted to engage the top inner edges of the circumferential plates and thus hold the funnel in position.

From the foregoing, it will be apparent that I have provided a multiple form for triangular posts which is compact and simple. Its component parts may be readily assembled or separated and there are fewer parts required by this form of assembly than in any other.

While I have described my invention with some particularity, it is to be understood that the words which I have used are words of description and not of limitation. And I wish it further understood that I am not limited to the precise details or combinations thereof disclosed in this application but that changes within the purview of the appended claims may be made without departing from the scope and spirit of this invention.

What I claim is:

1. A form or mold comprising a base provided with a plurality of recesses therein and angularly disposed plates forming a plurality of adjacent triangular prisms above and about said recesses.

2. In a form or mold for concrete posts, the combination with a vertically disposed post provided with means positioning vertically disposed plates radiating therefrom, of circumferentially disposed plates, and means for wedging the circumferential plates into tight contact with the radial plates to form a substantially unitary structure.

3. In a form or mold for concrete posts, the combination with a base having a centrally disposed post thereon and provided with a plurality of depressions about said post, of plates radiating from said post and coacting with positioning means on said base, circumferential plates, and means for wedging the circumferential plates into intimate contact with the radial plates to form a substantially unitary structure.

4. A form or mold for a post comprising a base provided with a recess adapted to mold an ornamental end on said post, separable plates removably mounted on said base, and means for holding said plates together to form a mold for the body of the post.

5. A form or mold comprising a base provided with symmetrically disposed depressions therein adapted to mold ornamental ends on a plurality of posts, radially disposed plates positioned between said depressions and coacting with positioning means

associated with said base, circumferential plates interposed between said radial plates to form laterally closed cells and means securing said last mentioned plates in position.

6. A form or mold comprising a base provided with depressions therein adapted to

mold ornamental tops on a plurality of posts, separable plates disposed about said recesses and rising from said base to form ¹⁰ a plurality of vertically extending cellular forms, and means for securing the whole in assembled relation.

CHARLES T. JOSLIN.
